(57) CLAIM

The ornamental design for a collapsible dish rack, as shown and described.

DESCRIPTION

FIG. 1 is a perspective view of a collapsible dish rack.
FIG. 2 is a front elevation view of the collapsible dish rack.
FIG. 3 is a rear elevation view of the collapsible dish rack.
FIG. 4 is a right side elevation view of the collapsible dish rack.

FIG. 5 is a left side elevation view of the collapsible dish rack.
FIG. 6 is a top elevation view of the collapsible dish rack; and,
FIG. 7 is a bottom view of the collapsible dish rack.

No claim is made to the texture or surface finish of the embodiments shown in the Figures.
